UNITED STATES PATENT OFFICE.

FRANK S. CLEGHORN, OF BROOKLINE, AND HARRY E. BARBER, OF BOSTON, MASSACHUSETTS.

SUPPORT.

Specification of Letters Patent. Patented Mar. 14, 1916.

1,175,706.

Application filed November 19, 1915. Serial No. 62,423.

To all whom it may concern:

Be it known that we, FRANK S. CLEGHORN and HARRY E. BARBER, citizens of the United States, and residents of Brookline and Boston, respectively, in the counties of Norfolk and Suffolk, respectively, and State of Massachusetts, have invented an Improvement in Supports, of which the following description, in connection with the accompanying drawings, is a specification, like characters on the drawings representing like parts.

This invention relates to supports and in its more specific aspects to supports which are designed to hold articles in an upright position. As an example may be mentioned the use for maintaining radiators suspended adjacent the walls of a room as disclosed in the embodiment of the invention here chosen for illustration.

My invention will be best understood by reference to the accompanying drawings illustrating various specific embodiments of my invention, wherein—

Figure 1 is a side elevation of a support in position, part of the article held thereby being indicated in dotted lines; Fig. 2 is a view of the support shown in Fig. 1 as seen from the right; Fig. 3 is a top plan view of the structure shown in Fig. 1; Figs. 4, 5 and 6 are side elevations of modifications of the support; Fig. 7 is a plan view showing a separable support; Fig. 8 is a section on the line 8—8 of Fig. 7; and Fig. 9 is a view partly broken away showing a modification of the support in which the parts are adjustable, the several parts being shown separated in the figure.

Referring now to Figs. 1, 2 and 3, in which we have shown one form of support embodying our invention, we have there illustrated a support comprising a base portion or attaching plate 1 adapted to be secured to the wall A by any suitable means such as the expansion bolt 2 on which the base plate 1 is preferably adjustable by means of the elongated slot 3. Extending from the base portion 1 is an arm or rest 4 which is adapted to hold an article suspended. In Fig. 1 the article is shown as a radiator B. We have termed the part of this arm which engages the radiator a rest since it takes up the weight of the radiator, and have shown it as a hook fitting the horizontal connection between adjacent

pipes or columns of the radiator, but it should be understood that it is not necessary in all cases that the arm extend beneath the article supported. Extending from the arm 4 preferably at a point intermediate between the base portion 3 and the extremity of the arm is the supporting member 6 which, in the modification shown, forms with the arm an angular article receiving holder. Suitable means are provided whereby the supported article, such as the radiator shown, may be clamped to the supporting member 6 so as to maintain it in an upright position on the rest formed by the arm 4. Such means are herein exemplified by the threaded rod or screw 7 which is disposed in a horizontal plane different from that of the arm 4 and enters the supporting member 6 at a point remote from the angle between the supporting member and the arm and the block 8 which acts as a washer to clamp the radiator B in place. In the embodiment shown the supporting member 6 will fit neatly in between adjacent upright pipes or columns of the radiator and the block 8 is formed tapered or wedge-shape and is journaled on the rod 7. It may therefore be placed between the adjacent pipes of the radiator from the outside and the rod manipulated also from the outside to set up the block against the pipes or columns and provide a firm clamping engagement (see Fig. 3).

It will be understood that in using our invention to suspend heavy articles such as radiators from walls that the base or attaching portion 1 must be secured to the wall proper which is composed of brick work or the like. When the wall is finished the usual coating of plaster C is applied to the wall A and will cover the base portion 1.

In Fig. 4 a modification of our invention is shown in which the clamping means to hold the article in upright position on the arm is illustrated as a bolt 9 hinged to the extremity of the supporting member 6 and provided with the wing nut 9'. It will be readily understood that the article is placed on the rest 4, the bolt 9 swung downwardly into any convenient recess therein and the nut set up to clamp the article in position.

The modification shown in Fig. 5 is essentially a reversal of that shown in Figs. 1, 2 and 3, the member 6^a extending vertically but downwardly instead of upwardly

from the supporting arm 4^a. In using a support constructed in this way the article depends from the rest 4^a and is clamped in place to the supporting member 6^a in precisely the same manner as in the modification of Figs. 1, 2 and 3. In this modification we have shown the base portion 1^a as of considerably greater depth than in Figs. 1 and 2, thus providing for a greater resistance to the turning moment developed by a heavy article.

In the modification of Fig. 6 the supporting member 6 does not appear as a separate member but is, so to speak, merged with the base or attaching portion. The attaching portion 1^b is similar to that shown in the other modifications but of considerably greater length. Adjacent one end thereof projects the arm or rest 4^b and near the other end we preferably provide the boss 6^b which receives the clamping screw 7^b similar to the screw 7 shown in the previous modification. The boss 6^b in a measure performs the functions of the supporting member 6 in that it provides for the proper positioning of the upper portion of the article which rests upon the horizontal supporting arm. We prefer, however, to utilize the member 6 for reasons which will hereinafter be explained.

In the modifications hereinbefore described the support has been of a permanent character, that is, when once secured in place by means of the bolt 2 it could not conveniently be moved. In Figs. 7 and 8 we have illustrated a modification where-in the article-holding portion of the support comprising the rest or arm 4 and the supporting member 6 is readily removable from the base or attaching portion. Referring now to these figures, it will be seen that we provide a base portion 1^c furnished with undercut ribs 10 which converge downwardly as shown in Fig. 8. The angular article-holding portion is made as a separate member and provided with the wedge-shape head 11 which fits between the ribs 10. Obviously the article-holding portion can be readily inserted and withdrawn from the upper side of the tapered slot formed by the ribs and it will be further understood that when the article is in position on the rest its weight will tend to drive the head 11 between the converging ribs and will cause the two parts of the support to interlock.

In using our device to hold articles supported on walls it is desirable to fasten it to the wall before any finish is applied thereto. Now it happens that the thickness of material used in finishing is not uniform. A plasterer lays a molding at the floor of the room and levels his wall up by it and considerable variations in the thickness of the layer applied may exist. Of course,

large and predictable variations of thickness are taken into account by choosing a suitable design of support in which the supporting member 6 is sufficiently distant from the attaching member 3. However, on account of the comparatively small and unpredictable variations which occur in practice it is at times desirable to have a support which may be adjusted so as to bring it to a fixed distance from the finished surface of the wall whatever may be the thickness of the finish. Such a support is illustrated in Fig. 9. We provide the base member 1^d having a hollow projecting boss 12. The article-holding portion comprises as before a rest 4^d and a supporting member 6^d extending vertically therefrom, to which is attached the clamping device 7^d as shown. Attached to the angular article-holder thus formed is the extension 13 which is adapted to fit easily into the hollow boss 12. Means are provided whereby the two members may be held in any desired position of adjustment and we have here shown teeth 14 at the bottom of the chamber in the part 12 and coöperating teeth 15 on the extension 13 which are adapted to interfit with the teeth 14. If desired a set screw 16 may also be used to hold the two members firmly in adjusted relation, but by virtue of the arrangement of interengaging teeth such as we have shown the weight of the article supported will act to hold the two portions of the support in interlocking relation.

By the use of a support such as we have described many advantages are attained. As an example, we will refer briefly to its use for the purpose of attaching radiators, it being understood that we do this simply for the sake of definiteness and not because we consider the invention limited solely to use with radiators. In preparing to fasten a radiator on the wall, holes are drilled in the wall and one of the supports, such for example as the one shown in Figs. 1, 2 and 3 fastened firmly in place. Laterally thereof a second support is placed in position and through the adjustment provided by the slot 3 it can readily be brought into horizontal alignment therewith before being made fast. Only a single row of supports is required to hold the radiator before it is fastened and consequently it is unnecessary to attempt the practically impossible feat of so placing different rows of fastening devices that they may all take a proper share of the load. After the wall is plastered up the radiator is next placed in position resting on and suspended by the arms 4 and then the clamping rods 7 and blocks 8 may be manipulated from the front of the radiator by the use of an ordinary screw driver to firmly clamp the radiator in an upright position against the supporting members 6. It will be ap-

parent that no exact vertical distance between the rod 7 and the rest 4 is necessary as the rod 7 is not required to be placed beneath any part of the radiator so as to support the direct thrust of gravity. Such a support as we have described is practically invisible when in place on the wall as both the rest portion of the arm 4 and the supporting member 6 are housed between adjacent pipes or columns of the radiator and the block 8 is, as it were, countersunk therebetween (see Fig. 1). It is partly for this reason that we prefer the structures shown in the other figures to that shown in Fig. 6 as a neater and much more sanitary structure is the result. The only projection from the surface of the wall in a support such as that shown in Figs. 1, 2 and 3 is the neck portion of the arm 4 where it joins the base portion 1 and it is possible to run a brush or broom behind the rest of the radiator with comparative ease. The advantages which accrue from having a radiator supported off the floor, both in convenience in not having to mutilate floor coverings and in cleanliness are too apparent to need enumeration here.

An important feature of our invention is that the radiator is secured along a very narrow vertical zone and that the support has what is practically one point contact with the wall. The base portion or attaching plate 1 is relatively quite small and consequently the bracket is not thrown out of plumb by irregularities of the wall as it would be if it extended for a considerable distance along the back of the radiator and can therefore be fastened securely directly to the brick work. The angular radiator-receiving portion grips the radiator, as it were, near its bottom for, while we have denominated the point of attachment of the screw 7 remote from the rest 4 this word is not to be taken as implying far distant in the ordinary sense. In fact the height of the arm 6 is comparatively small as compared to that of the radiator and the greater portion of the latter is therefore unrestrained and free to come and go as it expands and contracts under variations of temperature. When radiators are fastened at widely separated points along the vertical pipes the full amount of this strain is transmitted to the wall fastenings and may result in tearing them away or loosening them and in any event tends to crumble the plastering. By the use of our bracket which engages the radiator along a narrow zone most of the elongating and warping movements are not transmitted at all to the wall fastening and what is transmitted is concentrated through the neck of the arm 4 at a single point and there is no crushing and no bending of the plaster layer.

The use of the various modified forms of

the invention, whether as applied to radiators or to the support of other heavy and unwieldy articles will be sufficiently apparent from the description thereof and the remarks made in connection therewith.

70

In describing the illustrated embodiments of our invention, we have referred in some detail to their application as wall supports for radiators and that is indeed one of the fields in which we believe that great advantages will accrue from their use. It will be understood, however, that in thus referring to a specific application, our motive has been to make more readily comprehensible the use of our invention than would be the case if general and indefinite terms were employed and that we did not enter into such a specific description with a view of limiting the scope of our invention to a given application.

85

What we do claim and wish to secure by Letters Patent is:

1. A support for radiators comprising a supporting hook having means for attachment to a vertical wall and adapted to support a radiator, a member carried by the hook extending substantially vertically between the extremity of the same and the point of attachment thereof and forming a supporting member spaced from the wall and means coöperating therewith adapted to engage the radiator pipes to clamp the radiator toward said member whereby to hold the same upright for support by said hook.

90

2. A support for radiators of the type having spaced vertical columns comprising a holding portion which comprises a hook and an upright member at the base of said hook, said holding portion being of a size to be received between adjacent columns of the radiator, means to secure the radiator to said member in a horizontal plane different from that of said hook, a base plate adapted to be secured to a vertical wall and a neck connecting said plate and holding portion.

105

3. A radiator support comprising a base plate for attachment to a vertical wall and having a relatively small area to provide substantially a one point contact therewith, an angular radiator-receiving portion fitting the radiator and comprising a substantially horizontal supporting rest and a relatively short vertical arm, means coöperating therewith to clamp the radiator toward said vertical arm at a point in a different horizontal plane from said rest and relatively adjacent thereto whereby the radiator is held along a zone of low height and free response of the same to temperature changes is permitted and a neck connecting said receiving portion and base plate.

110

4. A wall bracket or support for holding a radiator suspended adjacent the wall of a room comprising a substantially horizontal radiator-suspending rest adapted to receive

120

125

- the horizontal connecting portion of the radiator between the adjacent pipes or columns and form a fulcrum support, a substantially vertical member associated therewith and presenting an abutment for engagement with the back of the radiator relatively close to the point of suspension and a clamping device entering between and engaging adjacent pipes or columns and manipulatable from the front while the radiator is on the rest to draw the same about its fulcrum against said abutment to hold the radiator upright on said rest by engagement with a comparatively narrow vertical zone thereof whereby a free response to temperature changes is permitted.
5. A radiator support comprising a relatively small base plate having means for attachment to a wall, an arm extending therefrom having a portion forming a rest for said radiator, a short supporting member extending from said arm adjacent said rest and spaced from said base plate and means to secure the radiator to said member in a horizontal plane separate from that of the rest but closely adjacent the supported portion of the radiator whereby the free expansion thereof is permitted.
6. A support for radiators having a receiving portion shaped to fit the radiator and including a rest to receive the base of the radiator and a supporting member ex-

tending along the side thereof, means to secure the radiator to said member closely adjacent the base thereof and means to attach 35 said receiving portion to a vertical wall in spaced relation thereto.

7. A device of the class described comprising a base portion, an article-holding portion comprising two members defining 40 an angle, one of said members constituting a rest, and means to secure the article to the other of said members at a point remote from the angle, said holding portion being adjustable toward and away from said base 45 portion.

8. A device of the class described comprising a base portion, an article-holding portion comprising two members defining 50 an angle, one of said members constituting a rest, and means to secure the article to the other of said members at a point remote from the angle, said holding portion being detachable from said base portion, the weight of the supported article causing them 55 to interlock.

In testimony whereof, we have signed our names to this specification, in the presence of two subscribing witnesses.

FRANK S. CLEGHORN.
HARRY E. BARBER.
